Harvey F. Crawford

UNITED STATES PATENT OFFICE.

HARVEY F. CRAWFORD, OF BROCKTON, MASSACHUSETTS.

SHANK.

1,245,877.

Specification of Letters Patent.

Patented Nov. 6, 1917.

Application filed November 14, 1916. Serial No. 131,348.

To all whom it may concern:

Be it known that I, HARVEY F. CRAWFORD, a citizen of the United States, residing at Brockton, in the county of Plymouth and State of Massachusetts, have invented certain Improvements in Shanks, of which the following description, in connection with the accompanying drawings, is a specification, like reference characters on the drawings indicating like parts in the several figures.

This invention relates to boots and shoes and more particularly to shank stiffening devices for use in the shank portions of boots and shoes.

In the manufacture of boots and shoes it is the usual practice to incorporate a shank stiffening device between the inner and outer soles of the shoe extending from the heel forwardly to approximately the ball line to maintain the arched formation of the shank portion of the shoe. A large number of these stiffening devices now in use are made of metal in order to provide an inexpensive stiffening device which will give the desired amount of rigidity to the shank of the shoe and provide adequate support for the foot without being too bulky and heavy. Such metallic shank stiffening devices are generally die-drawn from relatively thin metal sheeting and then tempered or otherwise treated to increase the rigidity of the metal plate. A serious objection to the use of the metallic shank stiffeners of this type is due to the fact that the relatively thin forward end of the stiffener tends to cut through the outer sole during the continual flexing of the shoe in wear. While it has been proposed to provide a curve at the forward end of the shank stiffener corresponding to the reverse curvature of the inner and outer soles at the ball line, this expedient has not been found entirely satisfactory, particularly since the forward end of the stiffener still has a tendency to cut into the outer sole when the sole is flexed out of its normal condition.

It is, therefore, an object of the present invention to provide a novel metallic shank stiffener which is so formed and arranged that the forward end of the stiffener is prevented from cutting through the outer sole during the continued flexing of the shoe in the act of walking. To this end the shank stiffening device of the present invention has its forward end formed and arranged to present a cylindraceous bearing portion

at the forward end of the stiffener in all the positions it assumes relatively to the outer sole during the wear of the shoe. In the illustrated embodiment of the invention the cylindraceous portion is formed by curling the material at its forward end abruptly downwardly and backwardly in such manner that the diameter of the cylindraceous portion is greater than the thickness of the plate from which the shank stiffener is made. This arrangement provides a substantially blunt bearing for the forward end of the shank stiffener which bearing is maintained during the flexing of the shoe in wear whereby the tendency of the forward end of the shank to cut through the outer sole, as with the shank stiffeners now in use, is entirely eliminated.

Other features and details of construction will be hereinafter more fully described in connection with the accompanying drawings, and the novel features will be set forth in the appended claims.

In the drawings,

Figure 1 shows a preferred embodiment of the shank stiffener of the present invention in position on the bottom of a shoe before the outer sole is applied.

Fig. 2 is a cross-section of the lower rear portion of a shoe illustrating the shank stiffener incorporated therein.

Referring to the drawings, the illustrated shank stiffener 2 comprises a relatively thin piece of sheet metal of a length sufficient to extend from under the heel of the shoe to approximately the ball line and of suitable width to be located between the inseams along either side of the shank portion of the shoe. This metal stiffener is arched between its ends to correspond to the longitudinal arch and also conformed to the transverse conformation of the shank portion of the shoe with which it is intended to be used. In order to give sufficient rigidity to the stiffener plate 2 to maintain the arched conformation of the shank portion of the shoe during wear and to provide adequate support for the foot, ribs 4 are formed on the upper surface of the plate, these ribs being preferably parallel to each other and extending nearly the entire length of the plate.

In accordance with this invention the forward end of the stiffener is prevented from cutting through the outer sole, during the continual flexing of the shoe in the act of walking, by providing the forward end of

- the stiffener with a transversely disposed cylindraceous bearing to engage the upper surface of the outer sole in the different relative positions it assumes on the outer sole.
- 5 In the illustrated embodiment of the invention this is accomplished by abruptly offsetting the material across the end of the plate downwardly and then bending or curling it upwardly and backwardly to form a cylindrically shaped portion disposed below the plane of the plate 2 as shown in Fig. 1. This cylindraceous portion may readily be formed at the same time that the plate is pressed into the desired shape and the ribs 10 4 formed so that there is no appreciable increase in the cost of manufacturing the shank stiffener. The diameter of the curl or the cylindrically shaped portion 4, as herein shown, is somewhat greater than the thickness of the plate 2 from which the shank stiffener is formed and is preferably approximately the same as the distance between the inner-sole and the outer sole of the shoe.
- 15 25 In the embodiment of the invention herein shown and described, the material at the forward end of the stiffener plate is abruptly bent downwardly and rearwardly to provide a cylindraceous portion offset below the plane of the shank stiffener. It is to be understood, however, that this showing and description are not intended to limit the invention since it is appreciated that the invention is applicable to use in connection with shank 30 35 stiffeners in which the cylindraceous bearing portion at the forward end of the stiffener differs both as to its relative location above or below the plane of the stiffener from the showing in the drawings and from the manner of providing the cylindraceous bearing portion at the forward end of the stiffener.
- To incorporate this shank stiffener in a shoe, the operator positions the stiffener upon the shank portion of the innersole and 40 45 secures it by a tack or other fastening means 8 at its rear end in the usual manner, the forward end of the shank stiffener locating itself approximately at the ball line of the shoe. It will be seen that when the soles of the shoe are bent at the ball line during the act of walking, the forward end of the shank stiffener presents a curved surface at all 50 55 times to engage the upper surface of the outer sole which effectually prevents the for-

ward end of the stiffener from cutting into 55 or otherwise breaking through the outer sole at this point.

Having described my invention, what I claim as new and desire to secure by Letters Patent of the United States is:

60

1. As an article of manufacture, a shank stiffener for boots and shoes comprising a metallic plate of relatively thin material arched between its ends and having its forward end formed and arranged to provide 65 an integral cylindraceous bearing across the forward end of the plate for all the positions it assumes relatively to the upper side of a shoe sole during the wear of the shoe.

2. As an article of manufacture, a shank 70 stiffener for boots and shoes comprising a metallic plate of relatively thin material arched between its ends and having the material at its forward end abruptly curled downwardly out of the plane of the plate and then rearwardly thereof across the entire width of the plate and constituting a blunt bearing for engagement with the upper side of a shoe sole.

75

3. As an article of manufacture, a shank 80 stiffener for boots and shoes comprising a metallic plate of relatively thin material arched between its ends and provided at its extreme forward end with an integral cylindrically shaped portion having a greater diameter than the thickness of the plate and constituting a blunt bearing for the forward end of the stiffener in all the positions it assumes relatively to the upper side of the shoe sole during wear of the shoe.

85

4. As an article of manufacture, a shank 90 stiffener for boots and shoes comprising a metallic plate of relatively thin material arched between its ends and having the material at its forward end formed and arranged to provide a cylindraceous portion extending across the end of the plate and offset from the plane thereof, said cylindraceous bearing having a diameter greater than the thickness of the plate and presenting at 95 all times a blunt bearing for engagement with the upper side of the sole of a shoe during the continued flexing of the sole in the act of walking.

100

In testimony whereof I have signed my 105 name to this specification.

HARVEY F. CRAWFORD.
